AEROSOL CONTAINER

Jo Sinel, 561 Clay St., San Francisco, Calif.

Filed June 2, 1958, Ser. No. 51,142

Term of patent 14 years

(Cl. D62—2)

FIG. 1

FIG. 2

I claim:

The ornamental design for an aerosol container, as shown.
